CLAIM

The ornamental design for a cookware handle, as shown and described.

DESCRIPTION

FIG. 1 is a top perspective view of a cookware handle according to the present invention.

FIG. 2 is a bottom perspective view of the cookware handle of FIG. 1.

FIG. 3 is a left side view of the cookware handle of FIG. 1, the right side view being a mirror image thereof.

FIG. 4 is a top view of the cookware handle of FIG. 1.

FIG. 5 is a front end (gripping end) view of the cookware handle of FIG. 1.

FIG. 6 is a rear end (mounting end) view of cookware handle of FIG. 1; and,

FIG. 7 is a bottom view of the cookware handle of FIG. 1.

The broken lines immediately adjacent the shaded areas represent the bounds of the claim and all other broken lines represent unclaimed portions of the design. None of the broken lines form a part of the claimed design.
